UNITED STATES PATENT OFFICE.

WILLIAM H. HOELL, OF GRAND CANE, LOUISIANA.

FASTENING DEVICE.

1,165,257.

Specification of Letters Patent. Patented Dec. 21, 1915.

Application filed May 15, 1913. Serial No. 767,889.

To all whom it may concern:

Be it known that I, WILLIAM H. HOELL, a citizen of the United States, residing at Grand Cane, in the parish of De Soto and 5 State of Louisiana, have invented new and useful Improvements in Fastening Devices, of which the following is a specification.

The present invention has reference to fastening devices, and it proposes an improved 10 mounting or attachment which, while designed primarily for application to shoe buttons, may be employed in connection with the fasteners utilized in gloves, corsets, skirts and other garments or articles of apparel.

15 The improvements comprehended in the invention are of such a character that the fastener, when in use, may be readily engaged with and disengaged from its complementary part without necessitating the use 20 of button hooks or other implements of a like character, and will compensate for expansion or muscular distention of the part of the body whereon the article to which it is applied is worn.

25 An embodiment of the invention is illustrated in the accompanying drawing, whereof:

Figure 1 is a fragmental front elevation of the fly portion of a shoe equipped with 30 the improved fasteners, a portion of the facing of the shoe being broken away to show the device in place against the lining; Fig. 2 is a rear elevation of Fig. 1, with part of the lining of the shoe and part of the 35 casing which surrounds the spring of one of the fasteners broken away, to disclose the mounting of the fasteners, the latter occupying different positions; Fig. 3 is a transverse section on line 3—3, Fig. 1; and Fig. 4 is a 40 detail view showing one of the fasteners.

In said drawing, 5 indicates, generally, the portion of the article to which the fastener proper 6 is applied, in the present instance, the aforesaid fly or fly portion of an 45 ordinary shoe. The fastener proper 6 is, accordingly, in this instance, constituted by a button of the usual type and is, of course, designed for co-operation with the button-hole, (not shown), which forms the complementary part of the fastening.

The outer layer or facing 7 of the fly is provided with a longitudinal slot 8, through 50 which the shank 9 of the button projects, and this slot is disposed transversely of said facing and is of sufficient length to allow a

bodily, lateral movement of the button of considerable extent. To provide for such movement, the button shank is connected to the adjacent end of a yielding or expandible and contractible element, here shown as a 60 retractile coil spring 10 which is formed of fine wire and is flattened. This spring is located between the outer layer or facing 7 and the inner layer or lining 11, and its other end is held in place by means of a stud 12, 65 or the like, to which it is loosely connected, said stud being passed through and fixed in the said facing 7. Hence, the spring is supported at one end by the stud, and at the other end by its connection to the button 70 shank, and is free to expand and contract in the space between the layers 7 and 11. Also, this arrangement prevents the spring from coming into contact with that part of the foot against which the fly bears, and thus 75 protects such parts. The spring may be inclosed in a flattened, tubular metal case or sleeve 13. This case is open ended, as will be understood, and is provided at its rear end with a perforated tab or eye 14, through 80 which the attaching stud 12 passes, the latter also having the rear end of the spring connected therewith.

The operation is believed to be obvious, but it may be stated that the button, or other 85 fastener proper, is normally held in position at the rear end of the slot by the tension of the spring, but may be drawn forward when it is to be engaged with the buttonhole or other complementary part of the fastening, 90 this extension mounting rendering the use of a buttonhook unnecessary, since the button can be readily manipulated by hand. For the same reason, the fastening will yield during muscular expansion, and will thus permit free movement of the part of the body 95 to which the article whereon it is used is applied. The employment of the case serves to remove the pressure of the stiff outer layer of material from the spring.

While the invention has been represented, and primarily described as applied to a shoe, it is to be understood as not limited to such use, but may be employed in connection with any of the other classes of garments or 100 articles of apparel originally specified. In each instance the construction and arrangement of parts are substantially as above recited; that is to say, the spring is disposed 105 between the facing and inner lining of the 110

garment and has connected with it, the button or other headed element, the shank of which projects through a slot in the facing.

Having described my invention, I claim:

The combination with an article of apparel embodying juxtaposed facing and lining layers, said facing layer being provided with a plurality of transverse slots; of flat retractile coil springs interposed in said layers and corresponding in number to said slots and arranged adjacent thereto; a flat tubular casing adapted to loosely surround each spring and being formed on one end with a perforated extension; a button for each slot; a shank projecting from each but-

ton and extending through said slots and rigidly connected to one end of the coil spring adjacent the respective slot; a securing stud for each of said springs and extending through said facing layer, perforated extension and connected with the opposite end of said spring, whereby the casing and spring are positively held in position. 20

In testimony whereof I have hereunto set my hand in presence of two subscribing witnesses. 25

WILLIAM H. HOELL.
